UNITED STATES PATENT OFFICE.

OTTO SCHIMANSKY, OF SANDUSKY, OHIO, ASSIGNOR TO SANDUSKY COOPERAGE & LUMBER COMPANY, OF SANDUSKY, OHIO, A CO-PARTNERSHIP.

GRATE-BAR.

SPECIFICATION forming part of Letters Patent No. 737,156, dated August 25, 1903.

Application filed July 13, 1903. Serial No. 165,297. (No model.)

To all whom it may concern:

Be it known that I, OTTO SCHIMANSKY, a citizen of the United States, residing at Sandusky, in the county of Erie and State of Ohio, have invented certain new and useful Improvements in Grate-Bars, of which the following is a specification, reference being had therein to the accompanying drawings.

The invention relates particularly to hollow grate-bars through which air-currents are adapted to pass to increase the combustion of the burning fuel; and it consists in the novel formation of the bar, and particularly in the peculiar construction of the caps covering the discharge-openings and their application to the bar, whereby a maximum airblast may be discharged within the arch and in all directions therein in such manner as to produce intense combustion.

The invention further consists in certain details of construction, as will be hereinafter more fully set forth, and shown in the drawings, in which—

Figure 1 is a broken plan view of a grate-bar embodying my invention. Fig. 2 is a broken side elevation in longitudinal section. Fig. 3 is a perspective view of the bar. Fig. 4 is a cross-section taken on line $\alpha\alpha$ of Figs. 1 and 2. Fig. 5 is a sectional perspective view of a portion of the bar, showing the construction of one of the draft-openings. Fig. 6 is a perspective view of the cap. Fig. 7 is a sectional plan view of a modification. Fig. 8 is a cross-section on line yy of Fig. 7; and Fig. 9 is an enlarged sectional perspective of a modified construction of bar, showing the discharge-opening.

The reference-letter A represents a grate-bar of any approved form and hollow, as illustrated. The bar is provided with a suitable air-inlet B and has formed in its top, which is flat, a plurality of discharge openings or outlets C. The walls about the discharge-openings are provided with annular seats D, upon which the caps E are mounted. The caps, as shown, comprise flat circular tops F, which are seated within the discharge-passages in the manner indicated and carry integral therewith inverted conical shanks G, which depend from the under face of the caps

and project a considerable distance within the grate-bar. These shanks serve a three-fold purpose, acting, first, as weights to hold the caps to their seats and prevent displacement upon shaking or poking of the fire. 55 Secondly, on account of the peculiar form of the shank it serves as a deflector for the blast of air entering the hollow grate-bar from the inlet, causing the air to pass through all of a series of draft-passages hereinafter described 60 arranged circumferentially about the cap. Thus a maximum amount of air is uniformly discharged within the usual arch which promotes combustion to such an extent as will permit the burning of all kinds of refuse. 65 Finally, the tapering shanks serve as guides for inserting the caps and enable the latter to be readily and quickly placed within the discharge-openings after their removal for purposes of cleansing or other reasons. The 70 draft-passages about the cap may be formed in various ways. In Figs. 1 to 5, inclusive, the openings are made by recessing the seats, so that a series of vertical passages b, spaced from one another, will extend therethrough, as plainly shown in Fig. 5. The cap proper in each instance is of less area than the area of the discharge-opening, which produces an annular space a between the cap and the walls of the opening. The air is discharged from the grate through the vertical openings b and the passage a. If desired, however, the cap-seats may be imperforate, as shown in Fig. 8, and a series of spaced lugs or projections c formed thereon. The 80 cap of relatively smaller size than the opening, as above set forth, rests in this instance upon the lugs, and the air passes between the cap and the seat and through the annular space a. The caps are also preferably arranged within the openings below the flat top of the grate, so that a poker or scraper used in stirring the fire will not disturb them. It is immaterial, however, in what particular manner the circumferential draft-passages 90 are formed, providing the caps are provided with the conical deflectors described, which cause the air to be discharged uniformly through all of the circumferential passages 95 for the purpose set forth. I do not desire to 100

be limited to the exact construction shown therefor, as the invention is susceptible of various modifications.

What I claim as my invention is—

- 5 1. In combination with a hollow grate-bar having an air-inlet, and a discharge-opening formed in its top, of a removable cap seated within said discharge-opening and carrying depending from its under face an inverted 10 conical shank projecting within the bar, there being a series of draft-passages arranged circumferentially about the cap leading from the interior of the grate.
- 15 2. In combination with a hollow grate-bar, having an air-inlet, and a discharge-opening formed in its top, of a flat imperforate cap removably seated within said discharge-opening below the grate-top and carrying depending from its under face an inverted conical 20 deflecting-shank projecting within the bar,

there being a series of draft-passages arranged circumferentially about the cap leading from the interior of the grate-section.

3. A hollow grate having an air-inlet and a plurality of discharge-openings formed in its 25 top, the walls about said openings being provided with flat annular seats, a plurality of spaced lugs upon each seat, flat caps seated within the discharge - openings below the grate-top of less area than the area of the 30 openings, and resting upon the lugs on the seats, and an inverted conical shank integral with each cap and depending from the under face of the latter within the grate-bar.

In testimony whereof I affix my signature 35 in presence of two witnesses.

OTTO SCHIMANSKY.
